UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,117,405.

Specification of Letters Patent.

Patented Nov. 17, 1914.

Application filed October 19, 1912. Serial No. 726,588.

To all whom it may concern:

Be it known that I, ALFRED G. F. KUROWSKI, a citizen of the United States, residing in Brooklyn borough, in the county of Kings, city and State of New York, have invented certain new and useful Improvements in Type-Writing Machines, of which the following is a specification.

This invention relates to typewriting machines, and is especially directed toward the escapement mechanism which feeds the carriage forward a letter-space at a time as the type keys are operated. It is herein illustrated as applied to an Underwood typewriting machine in which a universal bar is operated at every type-stroke by means of the type-bars. The carriage is spring-fed and is controlled in its feeding by means of said universal bar.

The carriage in the present invention may have fast on it a rack which is arranged to constantly engage a ratchet wheel and be driven thereby; said ratchet wheel being constantly under torque from a spring fast to its axle. This spring may be contained within a drum which engages said ratchet wheel by means of spring-pawls, so that when said carriage travels in letter-feeding direction, said drum travels with it, but in the opposite direction the pawls fail to catch the ratchet wheel and said drum may stand idle when the carriage is being returned to the beginning of a new line. The spring is re-wound by the carriage while the drum remains still. Said drum, in order to control the carriage, may comprise a rack cut on its surface in the form of crown teeth. This rack may comprise two sets of teeth facing each other. The above described universal bar may operate a dog which is arranged to alternately engage with each set of teeth and so permit said carriage to be drawn forward a step at a time as the pawl is moved from one set of teeth to the other. Provision may be made for moving this dog out of engagement with said drum and its rack so as to permit the carriage to be moved in letter-feeding direction without being arrested at every letter-space.

Other features and advantages will hereinafter appear.

In the accompanying drawings, Figure 1 is a sectional view of an Underwood type-writing machine. Fig. 2 is a front view of

certain parts of the escapement mechanism and carriage of said typewriter. Fig. 3 is a plan view of Fig. 2. Fig. 4 is a perspective view of the universal bar and the escapement mechanism. Fig. 5 is a view of some of the parts seen in Fig. 3, the escapement dog being in a different position. Fig. 6 shows the same parts in another position. Fig. 7 is a section through the spring and some adjacent parts. Fig. 8 is a front view of the driving ratchet.

In the Underwood typewriting machine, keys 1 depress key-levers 2 to swing bell cranks 3 to cause type-bars 4 to swing type 5 upwardly and rearwardly so as to write on a platen 6, which is rotatably mounted in a carriage 7. Said carriage has fast on it in the present invention a rack 8, by which it is driven through a ratchet wheel 9 meshing therewith; said ratchet wheel being driven by means of a spring 10. The feed of the carriage is controlled by a dog 11 which is vibrated in a rack 12 formed in the barrel surrounding said spring 10, the dog 11 actuated by a universal bar 13 operated by heels 14 on each type bar as the type bar approaches the platen. Said universal bar 13 is normally drawn forward by means of a spring 15, and as it moves rearwardly an abutment 16 adjustably mounted on said universal bar strikes said dog 11 near the point where it is pivoted and moves it rearwardly out of engagement with a tooth 17 in the forward side of said spring-barrel. This for a moment permits the spring 10 to turn slightly so as to draw the carriage forward, but as said dog 11 moves to the farther side of said spring-barrel, it engages the inclined face 18 of a tooth 19 on the opposite side of said spring-barrel, and prevents said barrel from turning materially as long as said type bar remains in its upright position with the type adjacent the platen 6. As soon, however, as the key lever is released, the type bar begins to return under the combined influence of the spring 15 and the inclined face 18; which inclined face tends to cam the dog 11 forwardly. When the universal bar 13 has been returned to its normal position under these combined influences, the dog 11 will have engaged the succeeding tooth 17 of the front side of the rack, and there will hold the carriage arrested. Said dog is, for purposes to be described later, pivoted at

20 on a swinging lever 21, and is drawn by a spring 22 attached to a short rearwardly extending arm 23 of the dog, so as to swing its end nearest the rack to normally engage 5 the front teeth 17 of the rack.

10 The spring 10, as will be seen from Fig. 7, is fast to the hub 24 of the ratchet wheel 9, which wheel turns freely on an axle 25 extending through a bracket 26 at the rear of 15 the typewriting machine. Said axle 25 carries fast on it by a pin 27 a casing 28 which comprises a flange 29, to which flange the opposite end of said spring 10 is attached. Said spring may be adjustably tightened by means of a handle 30 fast on said axle 25 and may be locked when tightened by means of a pawl 31 pivoted on the bracket 26 and engaging a ratchet 32 fast on the axle 25.

20 The rack 12 is formed as a flange 33 of a casing 34 also turning loose on the axle 25. Said rack, as has been stated, comprises two sets of crown teeth facing each other and the teeth in the forward side of said 25 rack are formed with one flat face 35, against which the dog 11 normally abuts, while the teeth of the opposite side are formed as inclined planes extending toward the front teeth. The rear ends of these 30 front teeth are so formed as not to interfere with the backward motion of the dog 11, and the rear teeth, (as best seen in Figs. 3 and 5) are flat at the point 37 where the dog will strike them as it moves rearwardly 35 under the influence of the universal bar 13.

40 It will be seen that when the universal bar moves forward after a type-stroke and its abutment 16 allows the dog 11 to come forward, the inclined face 18 of the tooth 19 will positively cam said dog forward into the path of the succeeding tooth 17 of the front rack. Teeth 17 (as best seen in Figs. 3 and 5) have a flat face 36 adjacent to the flat face 35, against which the dog 11 normally abuts, so as to leave an open space 45 between said teeth in which the dog 11 may play in returning to engage a tooth 17. The rack 12 is connected to the spring drum by means of its casing 34, which casing carries 50 two pawls 38 pressed by springs 39 against the ratchet wheel 9 to which the inner end of the spring 10 is fixed so that as said spring 10 unwinds, it will positively turn the ratchet wheel 9 and with it the 55 escapement rack 12. The teeth of the ratchet wheel 9 are of the ratchet shape usually employed in the escapement of the Underwood typewriting machine, and are arranged so that the bearing faces which contact with 60 the teeth of the rack bar 8 are practically vertical, and the teeth of said rack bar are of corresponding form. A roll 39^a may be provided upon the framework to run idly upon the rack just above the pinion 9 to 65 prevent the rack from jumping up from

the pinion. The rack bar 8 in order to take up any lost motion in the mechanism of the escapement, carries an auxiliary rack bar 40 which is slidably mounted thereon by means of pins 41 riding in slots 42 at the 70 ends of said rack bar 8. Said auxiliary bar 40 is normally drawn to the left, as viewed in Fig. 3, by means of a spring 43 drawing on a pin 44 projecting through a slot 45 in the main rack bar 8. The two rack bars 8 and 40, as seen in Fig. 8, have substantially identical teeth, and by means of the spring 43 are drawn so that their teeth are slightly offset from each other and so fill up the whole space between any two teeth 46 of the 75 80 ratchet wheel 9.

In order to release the carriage 7 from the escapement mechanism so that the carriage may be moved freely, the dog 11 carries a pin 47 which is arranged to be struck by a cam face 48 of a bar 49 slidably mounted on the main frame by means of pins 50 in slots 51 on said bar. As said bar 49 is moved rearwardly, the cam face 48 strikes the pin 47 on the dog 11 and draws said dog away from the escapement rack by swinging the dog with its pivoted bar 21 against the tension of spring 22. The carriage may then be moved freely in either direction since the dog 11 is out of engagement with the escapement rack 12. This rack-release may be operated by means of a bar 53 joining rock arms 54 at opposite ends of said carriage, one of which rock arms is formed with an extension provided with a handle 100 52. Said bar 53, as seen in Figs. 1 and 4, is arranged to strike the turned up end 55 of the bar 49 and so operate the cam 48. The pin 47 extends to the surface of the plate 21^a on which the pivoted arm 21 is 105 mounted, and so takes the downward thrust on the tail of the dog 11 due to the upward thrust on the point of the dog from the teeth 17.

The typewriter machine also comprises 110 a tabulating key 56 which, through a key lever 57, depresses a link 58 and swings a stop 59 adjustably mounted on a rock shaft 60 into the path of a stop 61 adjustably mounted on the carriage. Said 115 rock shaft 60 is joined by means of a rock arm 62 to the link 58 and carries a shaft 63 about which the stop 59 may be swung for adjustment by its handle 64. As the link 58 is depressed by the tabulating key 56, 120 it swings a rock arm 65 fast on the rock shaft 60, so as to strike a turned-up end 66 at the rear of the bar 49 and draw said bar rearwardly so as to cam the dog 11 out of 125 engagement with the escapement rack 17. In this way depression of the tabulating key at once moves a stop to operative position, and at the same time releases the typewriting machine from the escapement mechanism. 130

In order that the dog 11 may positively engage with the escapement rack 17, the stop 59 is so arranged with reference to the stop 61 as to arrest the rack 17 in such 5 position that the dog 11 will enter between the teeth of said rack a slight distance above the flat surface 35 of a tooth 17.

In order that the typewriting machine may be always arrested at the same part of 10 a letter-space, the number of teeth 46 on the ratchet wheel 9 is the same as the number of teeth in the rack 17. When the dog 11 is so drawn back, it is prevented from swinging too far in either direction by means of 15 a hood 67, which includes abutments 68 at either end of the throw of said dog 11, and the dog is held down close to plate 21^a by said hood 67.

It will be noted that this escapement will 20 have little of the clicking noise, found in most escapements, for the dog 11 is returned by the cam face 18 of the teeth 19 almost without the tension of the spring 22.

Variations may be resorted to within the 25 scope of the invention, and portions of the improvements may be used without others.

Having thus described my invention, I claim:

1. In a typewriting machine, a feed rack, 30 a pinion engaging therewith, an escapement wheel connected with the pinion, said wheel having a continuous zig-zag slot therein, and a movable stop working in said slot, said slot guiding said stop positively to successive 35 letter-space positions of rest.

2. In a typewriting machine, a feed rack, 40 a pinion engaging therewith, an escapement wheel connected with the pinion, said wheel having a peripheral zig-zag slot therein, and a movable stop working in said slot, said slot guiding said stop positively to letter-space positions of rest.

3. In a typewriting machine, a feed rack, 45 a pinion engaging therewith, an escapement wheel connected with the pinion having a set of spaced shoulders on its periphery and a set of oblique faces opposite said shoulders, and a stop guided by said oblique faces to engage said shoulders at letter-space positions of rest.

4. In a typewriting machine, an escapement wheel having a zig-zag slot formed therein, and a stop movable laterally in said slot and guided thereby to successive letter-space positions of rest, said stop also movable longitudinally into and out of position to control the rotation of said wheel.

5. In a typewriting machine, an escapement wheel having a set of spaced shoulders 60 on its periphery, a set of oblique faces opposite the shoulders, and a dog movable laterally to engage said shoulders, and guided by said faces during its return movement as the escapement wheel rotates.

6. In a typewriting machine, an escape-

ment wheel having a continuous zig-zag slot formed therein, a stop movable laterally in said slot to control the rotation of the said wheel and longitudinally movable out of position to control said rotation, and a spring 70 for holding the stop in engagement with the wheel.

7. In a typewriting machine, an escapement wheel having a set of spaced shoulders on its periphery, a set of oblique faces opposite the shoulders, a laterally and longitudinally movable dog engaging said shoulders at successive letter-space positions of rest under the positive guidance of said oblique faces, and a spring for holding the dog in 80 engagement with one of said shoulders.

8. In a typewriting machine, an escapement wheel having a zig-zag slot formed therein, a dog working in said slot and positively guided by the slot into position to arrest the escapement wheel at letter-space intervals and thereby prevent skipping, and a support carrying the dog and movable to withdraw the dog from operative position.

9. In a typewriting machine, an escapement wheel having a zig-zag slot formed therein, a dog working in said slot and positively guided by the slot into positions to arrest the escapement wheel at letter-space intervals and thereby prevent skipping, a support carrying the dog and movable to withdraw the dog from operative position, and a spring holding said dog in engagement with the wheel.

10. In a typewriting machine, a feed rack, 100 a pinion engaging the same, a drum connected with the pinion, said drum having a zig-zag slot formed on its periphery, a dog working within said slot, and positively guided by the slot into positions to intermittently arrest the drum, and an impelling spring within the drum.

11. In a typewriting machine, a feed rack, a pinion engaging the same, a drum connected with the pinion, said drum having a 110 continuous zig-zag slot formed on its periphery, a dog working within said slot and guided thereby into positions to form a positive stop for the drum and thereby arrest the feed rack at letter-space intervals, an impelling spring within the drum, and means for adjusting the tension of said spring.

12. In a typewriting machine, a feed rack, a pinion engaging therewith, an escapement drum connected with the pinion, a ratchet 120 wheel having a web and a circumferential flange extending within the drum, an impelling spring connected at one end to said flange, means forming a driving connection between the other end of the spring and the 125 pinion, and a pawl engaging the ratchet.

13. In a typewriting machine, a carriage, a feed rack, a pinion engaging therewith, an impelling spring for the carriage, an escapement wheel connected with the pinion, a piv- 130

oted arm, a dog lever fulcrumed thereon engaging said wheel, said arm being stationary during the normal operation of the dog, a slide having a cam face engaging said lever, 5 and means for actuating the slide to swing said arm on its pivot and move the lever longitudinally out of engagement with the wheel.

14. In a typewriting machine, a carriage, 10 a feed rack, a pinion engaging therewith, an impelling spring for the carriage, an escapement wheel connected with the pinion, a laterally vibratable dog engaging said wheel, a support on which the dog is pivoted for said 15 lateral vibration, a stop on the dog, a slide engaging said stop, a lever pivoted at each side of the carriage, and a rod connecting said levers, said rod engaging the slide to move said support and throw the dog out of 20 engagement with the wheel.

15. In a typewriting machine, a carriage, a feed rack, a pinion engaging therewith, an impelling spring for the carriage, an escapement wheel connected with the pinion, a laterally vibratable dog engaging said wheel, 25 a slide engaging the dog and having two up-turned ends, a tabulator frame having a projection extending therefrom, a lever pivoted at each end of the carriage, and a rod connecting 30 said levers, said rod engaging one of said up-turned ends, and said projection from the tabulator frame engaging the other of said up-turned ends of the slide to throw the dog out of engagement with the wheel.

16. In a typewriting machine, an escapement mechanism comprising an escapement wheel having a zig-zag slot in its periphery, a laterally vibratable dog working in said 40 slot, and a universal bar actuating the dog in one direction, said slot providing cam faces to engage and return the dog as the escapement wheel rotates.

17. In a typewriting machine, the combination with a carriage, of an escapement 45 wheel for said carriage, a crown rack on said wheel, a pivoted dog vibratable transversely of said rack, and a universal bar arranged to strike said dog and vibrate it on its pivot in one direction, said rack having 50 cam faces to return the dog and universal bar.

18. In a typewriting machine, the combination with a carriage, of an escapement wheel for said carriage, crown teeth on said 55 wheel having a flat surface, a dog arranged to hold said wheel by said teeth, a universal bar arranged to rock said dog out of said teeth, and cam teeth on said wheel arranged to return said dog by the rotation of said 60 wheel.

19. In a typewriting machine, the combination with a carriage, of an escapement wheel for said carriage, crown teeth on said wheel having a flat surface, a dog arranged 65 to hold said wheel by said teeth, a universal

bar arranged to rock said dog out of said teeth, a spring tending to return said dog, and cam teeth on said wheel arranged to return said dog by the rotation of said wheel.

20. In a typewriting machine, the combination with a carriage, of an escapement wheel for said carriage, crown teeth on said wheel having a flat surface, a dog arranged to hold said wheel by said teeth, key-operated type-bars, a universal bar arranged 70 to be moved by said type bars as they reach the printing point, and abutment on said bar arranged to rock said dog, and cam teeth on said wheel arranged to return said dog and said universal bar by the rotation of 80 said wheel.

21. In a typewriting machine, the combination with a carriage, of an escapement wheel for said carriage, a crown rack on said wheel, a dog, means to swing the dog in 85 one direction transversely of said rack to release said wheel, said rack having cam faces to return the dog as the wheel rotates, a pivoted arm which carries said dog, and means for withdrawing said dog from said 90 rack by swinging said arm.

22. In a typewriting machine, the combination with a carriage, of an escapement wheel for said carriage, a crown rack on said wheel, a dog vibratable transversely of said 95 rack, a pivoted arm which carries said dog, means for withdrawing said dog from said rack by swinging said arm, and a single spring tending to swing said dog transversely and to return it to engage said rack. 100

23. In a typewriting machine, the combination with a carriage, of a rack on said carriage, an escapement wheel constantly meshing with said rack, an escapement dog co-operating with said wheel to control the letter-space movements of the carriage, said dog positively operated by said wheel during each letter-space movement, into position to lock the wheel, a swinging support for the dog stationary during the normal 110 operation of the dog, and a key on the carriage arranged to withdraw said support and dog from said wheel.

24. In a typewriting machine, the combination with a carriage, of a rack on said carriage, a driving wheel comprising a spring constantly engaging said rack, escapement teeth on said wheel comprising teeth having flat faces and teeth having cam faces, a single dog controlling said escapement 120 wheel by said teeth, and means for withdrawing said dog from said wheel. 115

25. In a typewriting machine, the combination with a carriage, of a rack on said carriage, a driving wheel constantly engaging 125 said rack, a spring to drive said wheel, a second rack concentric with said wheel, a pawl and ratchet connection between said second rack and wheel, a single dog engaging said second rack to control said carriage. 130

- and means for moving said dog out of engagement with said second rack.
26. In a typewriting machine, the combination of a carriage rack, a pinion to drive the rack, a spring acting directly on said pinion, a cylindrical casing inclosing said spring and connected to said pinion, said casing having a zig-zag groove formed in its periphery, and an escapement dog working in said groove. 10
27. In a typewriting machine, the combination with a carriage, and an escapement mechanism controlling the movement of the carriage, said mechanism comprising an escapement wheel, of a drum housed within said wheel and rotatable relatively to the escapement wheel, and a carriage-driving spring within said drum. 15
28. In a typewriting machine, the combination with a carriage, of a rack thereon, a pinion in mesh with said rack, an escapement wheel connected to said pinion, a drum within said wheel, and a carriage-driving spring within said drum, and having its ends connected respectively to the drum and to the hub of the said pinion. 20
29. In a typewriting machine, the combination with a carriage, of a rack thereon, a pinion in mesh with said rack, an escapement wheel connected to said pinion, a drum within said wheel, a carriage-driving spring within said drum, and having its ends connected respectively to the drum and to the hub of the said pinion, means to rotate said drum to adjust the tension of said spring, and means to hold said drum in adjusted position. 35
30. In a typewriting machine, the combination of a stationary support, a shaft journaled therein, a pinion loose on said shaft, a rack in mesh with the pinion, a drum fixed to said shaft, a spring within the drum and connected at its ends respectively to the drum and the hub of said pinion, and a pawl and ratchet connection between the drum and said support. 40
31. In a typewriting machine, the combination of a stationary support, a shaft journaled therein, a pinion loose on said shaft, a rack in mesh with the pinion, a drum fixed to said shaft, a spring within the drum and connected at its ends respectively to the drum and the hub of said pinion, a pawl and ratchet connection between the drum and said support, an escapement wheel surrounding the drum, and a one-way driving connection between the escapement wheel and said pinion. 45
32. In a typewriting machine, the combination with a carriage, of a rack thereon, a pinion in mesh with said rack, means to drive said pinion, a second rack in mesh with said pinion, and a spring connecting said racks to take up play between the pinion and said first-named rack. 50
33. In a typewriting machine, the combination with parallel racks, of an escapement dog working between said racks, one of said racks comprising cams for positively moving the dog into engagement with the teeth of the other rack, and thereby causing the dog to hold said last-named rack. 70
34. In a typewriting machine, the combination of parallel racks, the teeth of one rack being offset with respect to the teeth of the other rack, cam faces connecting the successive teeth of one rack, and an escapement dog working between said racks and positively moved by said cam faces into holding engagement with the teeth of the other rack. 75
35. In a typewriting machine, the combination with an escapement rack and an escapement dog, of a movable support on which the dog is pivoted, means for laterally moving said dog with respect to the escapement rack, and a single spring to return said dog and also hold said dog and support with the dog against the escapement rack. 80
36. In a typewriting machine, the combination with an escapement wheel, an escapement dog having one end in contact with said wheel, a support on which said dog is pivoted for vibration laterally with respect to the wheel, said support being movable to withdraw the dog from the wheel, and a spring to move said dog about its pivot in one direction, and also exerting an endwise pull on the dog to hold it against said wheel. 85
37. In a typewriting machine, the combination with type-bars and a universal bar in the path of the type-bars to be operated thereby, of a pivoted escapement dog in the path of the universal bar and directly operated thereby, and an escapement rack with which said dog engages, said dog alone controlling the step-by-step movement of the said rack. 95
38. In a typewriting machine, the combination with type-bars, of a universal bar in the path of said type-bars to be operated thereby, a pivoted arm, an escapement dog pivoted to said arm in position to be engaged and operated directly by the universal bar, an escapement wheel, said dog having one end in contact with the wheel, and extending radially therefrom, a spring to return the dog when the universal bar is retracted, said spring operable also to hold the dog against the escapement wheel, and means to swing said arm and carry the dog out of contact with the escapement wheel. 110
39. In a typewriting machine, escapement mechanism comprising an escapement dog and parallel racks, said dog having a reciprocating movement between the racks to permit a step-by-step movement of the racks, the teeth of said racks each comprising a face perpendicular to the direction of 120
- 60
- 65

its rack, and an inclined face, said inclined faces forming inclined guideways in which the said dog is guided throughout its movement in one direction, and said perpendicular faces forming horizontal guideways in which the escapement dog is guided during its movement in the opposite direction.

40. In a typewriting machine, the combination with an escapement rack, of a dog 10 coöperating therewith to permit letter-feed movement of the rack, said rack having holding surfaces engaged by the dog to hold the rack stationary at intervals corresponding to letter-space movements, said rack having 15 an uninterrupted advance movement from the time the dog is released from one holding surface until it engages the next holding surface, whereby the complete advance of the rack for each letter-space is effected by a single continuous movement of 20 the rack, and cam surfaces each arranged to positively move the dog after it has been released from one holding surface and during the advance of the rack into position to 25 engage the succeeding holding surface.

41. In a typewriting machine, the combination with a carriage, of letter-feed mechanism controlling the movement of the carriage, said mechanism comprising an escapement rack having a series of holding surfaces, a dog arranged to reciprocate transversely to the rack and successively engage said holding surfaces during the letter-feed advance of the rack, said dog movable laterally in one direction out of engagement with each holding surface, and cams to positively return the dog to position to engage each succeeding holding surface, the movement of the rack being continuous throughout each 40 letter-space advance.

42. In a typewriting machine, the combination of escapement mechanism comprising a member provided with a zig-zag guiding surface comprising transverse rest portions 45 or holding surfaces connected by inclined guiding portions, and a coöperating dog guided by said zig-zag surface and operative when in contact with said rest portions to

hold said member stationary, said dog positively guided by said inclined portions during the letter-feed advance of said member into positions to engage the succeeding rest portions, thereby positively preventing skipping.

43. In a typewriting machine, the combination with letter-feed mechanism comprising an escapement member provided with a zig-zag groove or guiding slot therein, said slot comprising rest portions or holding surfaces at intervals measuring the advance of 60 said member for each letter-feed operation of the mechanism, said rest portions connected by inclined portions, of a dog working in said groove, a swinging support on which said dog is pivoted, a spring holding 65 said support in position to retain the dog in said groove, and also normally holding the dog in a lateral position in the groove to engage a holding surface or rest portion therein, a universal bar to swing the dog laterally out of engagement with said holding surface and permit said escapement member to advance, an inclined portion of the guiding slot operating during the advance of 70 said member to positively return the dog to position to engage the succeeding holding surface and also through said dog to return the universal bar, and key-operated means 75 for swinging said support and withdrawing the dog from said escapement member.

44. In a typewriting machine, the combination of a feed rack, a pinion engaging therewith, an escapement wheel connected to rotate with the pinion, said wheel having a series of spaced shoulders and a series of oblique faces extending from the shoulders, and a stop having a reciprocating movement transverse to the rotation of the wheel, said stop movable in one direction into engagement with said shoulders and guided in its 85 return movement by said oblique faces as the wheel rotates.

ALFRED G. F. KUROWSKI.
